WALTER GROTHE, OF SAN LEANDRO, CALIFORNIA, ASSIGNOR TO CATERPILLAR TRACTOR CO., OF SAN LEANDRO, CALIFORNIA, A CORPORATION OF CALIFORNIA

FURNACE

Application filed July 9, 1928. Serial No. 291,322.

My invention relates to furnaces primarily intended for use in heat treating material and particularly relates to a furnace of this type which is heated by electricity.

5 An object of my invention is to provide a furnace which is well insulated to conserve heat, with the insulating material occupying a minimum of space.

Another object of my invention is to provide 10 a furnace which can be quickly cooled from operating temperature.

Another object of my invention is to provide means for rendering the interior of the furnace quickly and easily accessible.

15 A further object of my invention is to provide means for supporting a portion of the interior structure from the top of the furnace.

An additional object of the invention is 20 to provide, in a furnace having a power rotated hearth, a manual rotating means taking precedence over the power rotating means.

A still further object of the invention is 25 to dispense with the usual framework of refractory material for supporting the heating elements.

My invention possesses other advantageous features, some of which with the foregoing will be set forth at length in the following description where I shall outline in full that form of the furnace of my invention, which I have selected for illustration in the drawings accompanying and forming 35 part of the present specification. In said drawings I have shown one form of furnace embodying my invention, but it is to be understood that I do not limit myself to such form since the invention, as set forth in the claims, may be embodied in a plurality of forms.

In the drawings:

Fig. 1 is a plan of the furnace of my invention with the cover removed to disclose 45 some of the bracing.

Fig. 2 is a vertical section of my furnace, the plane of section being indicated by line 2-2 of Fig. 1.

50 Fig. 3 is a section on a plurality of planes,

these planes being indicated by line 3-3 of Fig. 2.

Fig. 4 is a side elevation showing in detail a portion of the rotating mechanism for my furnace.

55 Fig. 5 discloses the door actuating mechanism.

Fig. 6 shows the central shaft, with some of its associated parts in section.

In its preferred form, the furnace of my invention comprises a shell within which is a revolving hearth, arranged to be moved into and out of operative position, and also usually includes an inner wall suspended so as not to interfere with the hearth.

60 In the embodiment illustrated in the accompanying drawings, the furnace comprises an outer shell 6 reinforced by a channel 7 at its lower circumference and resting upon a suitable base 8. The shell 6 is conveniently a metal cylinder stiffened at its upper end by a channel 9 and closed by a cover 11. Within the shell 6 I preferably provide an outer wall 12 usually comprised of refractory insulation 13 conveniently held in place and backed by a suitable heat-insulating substance 14. The outer wall is generally arranged in a cylindrical form and is largely supported in the upper portion of the shell 6 by brackets 16 and 17 properly secured in place. Inasmuch as the refractory insulation does not extend for the full height of the shell, there is provided an upper, thermally insulated zone in which the furnace heat is well retained and a lower, uninsulated zone in which radiation and dissipation of heat are relatively rapid.

65 Preferably concentric with the outer cylindrical wall 12, I provide an inner wall 18 likewise of refractory insulation 19 and suitable heat insulating material 21. The inner wall is generally of cylindrical form and preferably is supported from above. The suspension is preferably effected by a pair 70 of parallel I-beams 22 and 23 which extend substantially diametrically across the shell 6 at its upper portion and between them support a plate 24 having a collar 27 into which is threaded a centrally depending, 75

hollow column 26. The lower end of the column 26 is similarly threaded into a collar 28 forming a part of a platform 29 of sufficient extent to underlie the central wall 18. The weight of the inner lining is thus borne by the I-beams 22 and 23 through the medium of the hollow column 26 and is finally transferred to the outer shell 6. The annular space 31 occurring between the inner wall 18 and the outer wall 12 is bridged over by suitably arched insulating refractory members 32 usually interlocked with the members 13 and 19 and covered with the insulating material 21.

Within the furnace I preferably provide a revolving hearth to carry the parts to be treated. This hearth 33 generally includes suitably arranged refractories disposed on an annular table 34 comprised of a pair of 20 annular castings. The table at its inner and outer peripheries is formed with troughs 36 carrying sand 37 or other suitable sealing material into which project an annular ring 38 depending from the bracket 17 and an 25 annular ring 39 depending from the platform 29. In this manner there is provided a seal against heat loss and at the same time relative rotation and some axial translation is permitted between the hearth 33 and the stationary inner and outer linings 18 and 12.

The table 34 is mounted on a spider 41 which carries at its hub 42 a threaded sleeve 43 in engagement with the threaded portion 44 of a central shaft 46. The shaft 46 extends vertically throughout the shell 6 and at its lower end rests on a thrust bearing 47 suitably located within and protected by a casing 48 supported on the base 8 and positioned by stay rods 49 extending radially to the lower periphery of the shell 6. Shaft 46 is further provided with bearings 51 and 52 located at opposite ends of the hollow column 26 and designed to carry radial loads.

Ordinarily, it is intended that the spider 41 and the shaft 46 rotate as a unit and for this reason a two piece lock-nut 53 engages the threaded portion 44 and holds the hub 42 firmly in engagement with washers 54 bearing on a shoulder in the shaft 46. Inasmuch as the spider 41 normally does not travel axially along the shaft 46, I provide a cover for the unused threaded portion in order to protect it from dirt. This cover may be a shield made in two pieces 56 and 57 united at either end by bolts 58 passing through split collars 59.

Means are provided for imparting a slow rotation to the central shaft 46 in order to 60 revolve the hearth 33. This mechanism is particularly shown in Figs. 1, 2 and 4, which disclose a pair of cross members 61 and 62 spanning the beams 22 and 23. Suspended between the beams is an electric motor 63 which drives a reduction gear 64 supported

between the members 61 and 62. Projecting upwardly from the reduction gear is a crank pin 66 carrying a rectangular block 67 slideable between the parallel tines of a fork 68 forming one end of a bell crank 69 pivoted at 70 to a lever which in turn is freely rotatable on the central shaft 46. The other arm 72 of the bell crank is adjustably connected through a spring 73 to the lever 71. A stop 74 constrains relative movement of the bell 75 crank 69 and the lever 71 in one direction. The rotary movement of the electric motor 63 is transmitted through the reduction gearing 64 and revolves the pin 66. This movement is effective to reciprocate the block 67 within the fork 68 and imparts an oscillating movement to the lever 71. If for any reason the lever 71 cannot follow the movement of the bell crank 69 there is relative motion about the pivotal point 70 permitted by the yielding of spring 73 and the mechanism is thus prevented from transmitting excessive loads. The oscillating movement of arm 71 is translated into rotary movement of the shaft 46. A pawl 75 is pivoted to the arm 71 and engages a ratchet 76 formed on the periphery of a disc attached securely to the shaft 46. In order to constrain reverse movement of the central shaft and its attached hearth 33, a 80 brake drum 77 is secured to the upper end of a shaft 46 and is encompassed by a pair of bands 78 which are pressed together by a spring 79 and are adjustably anchored in a yoke 81 secured to the plate 24. The brake 80 exerts a sufficient retardant force to preclude rotary movement of the hearth 33 except under the superior urging of the ratchet device. The described mechanism is effective to rotate the hearth continuously at any 85 selected speed while the rate of rotation can easily be varied by changing the ratio of the reduction gear 64 and by altering the location of the crank pin 66 with respect to its 90 rotational axis.

Preferably, I also provide a supplementary, manually operated means for rotating the hearth through the intermediary of the shaft 46 and this usually comprises a yoke 83 freely journaled on the central shaft 46 and carrying between its arms a pawl 84 pressed against the ratchet wheel 76 by a spring 86. The yoke terminates in a handle 87 extending to a convenient point of hand operation alongside the shell 6. By manually rotating the hearth it is possible, without in any way interfering with the power drive, to examine any portion of the material being treated and to restore the hearth to its original position.

Access to the interior annular chamber 31 within which are placed the articles to be treated, is afforded through a sliding door. This door preferably comprises a block 91, made up of suitable insulating material, 130

- adapted to slide vertically in an opening 92 provided in the shell 6. The block 91 is vertically reciprocated by a pair of rods 93 at their lower ends joined by a cross member 94 and sheathed in guiding tubes 96. The vertical movement of the rods and of the door is adjustably limited by an auxiliary rod 97 carrying adjusting nuts 98. The rod passes through an aperture in a portion of a frame 99 secured to the shell. In order to counterbalance the weight of the block 91 and its operating mechanism, cables 101 are preferably secured to the cross member 94, pass over pulleys 102 journaled in the shell 6 and carry counterweights 103 at their opposite ends. The cross member 94 is vertically translated by a lever 104 joined to it by links 106 and rotatable with a shaft 107 suitably journaled on the shell 6. The end of the shaft 107 carries a handle 108 conveniently disposed for actuation by the operator. Preferably the relationship and adjustment of the actuating linkages for the door 91 are such that the top of the door when lowered is exactly flush with the floor of the opening 92, as indicated by the dotted lines 109, in Fig. 2. Thus there is formed a continuous and smooth passageway for the materials being inserted into or withdrawn from the furnace. Further, by arranging the door 91 to rise from below, it is possible to utilize full insulation above the door where large heat losses would otherwise occur.
- The heat is supplied to the furnace preferably by electricity and emanates from resistance ribbon 113 suitably suspended around the interior of the furnace on pins 114 directly embedded in the insulation thus dispensing with auxiliary support. Leads for the resistance element 113 and for pyrometers or other instruments are preferably carried to the interior of the furnace through passages 115 in suitable blocks 116 of refractory insulating material held in place by metal straps 117 secured to the shell and having bolts 118 which clamp the blocks 116 in place.
- In the usual operation of my furnace the parts have the relative positions shown in Fig. 2. When electric current is passed through the resistance material 113, the entire chamber 31 is heated with very slight thermal loss due to the effective insulation in the upper zone of the furnace. Pieces of material for treatment are inserted past the momentarily lowered door 91 onto the hearth 33 which is revolved during the normal operation of the furnace by the mechanism driven by the electric motor 63. When the pieces have made substantially a complete revolution, they are withdrawn from the furnace through the opening 92 and generally are replaced by untreated pieces. Occasionally a furnace of this type be-
- comes jammed or for other reasons it becomes necessary to gain access to the interior, for instance to renew the sand seals or to clean out scale deposited by the work. In ordinary furnaces it requires a period of 70 time usually measured in days to cool the furnace sufficiently to allow work on the interior thereof. With my construction it is possible to get at the interior within a time measured in hours or minutes. Since the 75 thermal insulation of the furnace is very complete and effective, heat is largely confined to the upper zone, and an operator can readily enter the lower portion of the shell 46 through suitable man holes 121. When 80 the shields 56 and 57 and the lock collar 53 are removed, the shaft 46 and the spider 41 can be relatively rotated to lower the hearth 33 into the thermally uninsulated lower zone of the shell 6. Usually when the bottom 85 lining 33 is thus lowered whatever difficulty has arisen can be rectified by suitable tools used through the man holes 121 but in any case the entire furnace cools quickly largely due to the rapid radiation of heat through the uninsulated lower shell 6 and to air currents which can be established through the man holes 121 and also through the opened door 91.
- It will be appreciated that I have provided a furnace which normally is very effectively sealed and insulated against the loss of heat and which therefore operates quite economically. The furnace, however, is capable of being adjusted so that it will 90 cool off very quickly and access to the interior can be had with dispatch. These features are largely due to the fact that the insulation and hearth are disposed and supported in such a way that the shell is divided into a thermally insulated zone and a thermally uninsulated zone and because the hearth can be raised and lowered with celerity.
- I claim:
1. A furnace comprising a shell, a screw shaft in said shell, means for rotating said screw shaft, a hearth mounted on said screw shaft for translation upon relative rotation therebetween, and means for preventing relative rotation between said screw shaft and said hearth. 110
  2. A furnace comprising a shell, a rotatable screw shaft within said shell, and a rotatable hearth threadedly engaging said screw shaft to translate said hearth with respect to said shell upon relative rotation between said screw shaft and said hearth. 115
  3. A furnace comprising a shell, a rotatable screw shaft within said shell, a rotatable hearth threadedly engaging said screw shaft to translate said hearth with respect to said shell upon relative rotation between said screw shaft and said hearth, and means 120
  - 65 125
  - 130

for rotating said screw shaft and said hearth in unison with respect to said shell.

4. In a furnace employing a rotating hearth, a driving mechanism for rotating the hearth at a substantially constant speed, and manual means superior to the driving means for moving the hearth.

5. In a furnace employing a rotatable hearth, a driving mechanism therefor including a power source and a ratchet mechanism for transmitting power to the hearth in a predetermined quantity and in only one direction.

6. In a furnace employing a rotatable hearth, a driving mechanism therefor comprising a power source, a ratchet mechanism including a lever for rotating the hearth, and a connection between the lever and the driving mechanism for transmitting only an approximately predetermined quantity of power to the hearth.

7. A furnace comprising an outer shell, an outer wall in the upper portion of said shell, an inner wall suspended in the upper portion of said shell, a hearth supported on and rotatable with respect to a screw for raising said hearth into operative relationship with said inner and said outer walls, and means for rotating said hearth and said screw as a unit.

8. A furnace comprising a circular outer shell; an outer wall in the upper portion of said shell; an inner wall in the upper portion of said shell, said walls being separated by an annular space; means for supporting said inner wall from the upper part of said shell; a central shaft in said shell; a spider threaded on said shaft and adapted to be raised and lowered thereon; means for rotating said spider and said shaft as a unit; and a hearth resting on said spider.

9. In a furnace, a hearth, and a shaft rotatable to raise, lower, and rotate said hearth.

10. In a furnace, a hearth, and a screw to adjustably support and to rotate said hearth.

In testimony whereof, I have hereunto set my hand.

WALTER GROTHE.
